UNITED STATES PATENT OFFICE.

JOHN M. BURKE, OF SCRANTON, PENNSYLVANIA.

APPARATUS FOR FILLING CUTS.

1,068,312.

Specification of Letters Patent.

Patented July 22, 1913.

Application filed May 7, 1912. Serial No. 695,610.

To all whom it may concern:

Be it known that I, JOHN M. BURKE, a citizen of the United States, and residing in the city of Scranton, county of Lackawanna, 5 and State of Pennsylvania, have invented a certain new and useful Apparatus for Filling Cuts, of which the following is a specification.

This invention relates to apparatuses for 10 filling depressions, such as ravines, cuts, or valleys, and for making roads, railway road beds, aqueducts, embankments, canals, etc.

The objects I have in view are to avoid 15 the necessity of using false work, and to employ, instead, simple and easily erected and operated apparatus.

Further objects are to reduce the height of 20 the towers which support the cable, to avoid the necessity of moving the anchors or dead men, at the ends of the cable, and to simplify 25 the adjustment of the parts, as the work progresses.

These and further objects will more fully appear from the following specification and 25 accompanying drawings, considered together or separately:

In the drawings, Figure 1 is a diagrammatic view showing a cut, or depression, to be filled, and illustrating the supporting 30 towers and cables at the preliminary stage of the work. Fig. 2 is a similar view, showing the operating parts assembled, also showing the beginning of the fill. Fig. 3 is a similar view, showing a further stage of operation, with the fill about one-half completed. Fig. 4 is a side elevation of the supplemental tower, in position to be moved. Fig. 5 is a front elevation of the same, and Fig. 6 is a view similar to Fig. 4, showing 40 the supplemental tower when it is in fixed position.

In all of the views, like parts are designated by the same reference characters.

Referring to the drawings,—1 represents 45 the cut, or depression, to be filled. This cut, or depression, may be of any depth or width, provided the width does not exceed the length of the cable, and the height of the towers which support the same is sufficient 50 to support the bight of the cable at the proper height. On one side of the cut is a tower 2; and on the opposite side is a tower 3. These towers are preferably made of metal. They are of such a height that the

center part of the cable will be supported at 55 a sufficient elevation to retain the suspended bridge structure, to be described, at the proper elevation. The towers are preferably permanently fixed in position, as they do not have to be moved during the progress of the 60 work. 4 represents the embankment, or fill, which is made by dumping earth or rocks or other filling material from dumping cars supported upon suitable tracks about to be described. A cable 5, is stretched over the 65 towers 2 and 3. In the embodiment chosen for illustration, there are two cables. It is apparent, however, that if desired, a single cable may be employed, with connections with the suspended bridge structure, being 70 so made as to be supported upon a single cable. The ends of the cables are anchored to suitable dead men 6. These dead men are buried in the ground at the proper place, so that the cables will have the requisite lead 75 up to the tops of the towers. The towers have side members, with an opening between them so that the track can be laid for the passage of the cars and locomotive to transport the material to the fill. These tracks 80 extend to and are supported by the suspended bridge structure 7. This suspended bridge structure is preferably flexible, so that it will yield when the cars pass upon it, owing to the bending of the cable. Any suitable bridge structure can be employed. One suitable for the purpose is illustrated in the patent of W. A. Wood, No. 951,874, dated 85 March 15, 1910. This suspended bridge structure is carried upon the pulleys (not shown) on the cable in such a manner that it may be moved along the latter as the work progresses. These pulleys are not illustrated, as they may be the same as those 90 illustrated in the Wood patent before referred to.

It is apparent that as the work progresses, and the bridge structure is moved toward the place about halfway between the towers, the weight on the cable will bend the latter so 100 that the bight of the cable will be extended below the level of the fill unless the towers 2 and 3 are made inconveniently high. In order to avoid this, and secure a support for the cable to lift the bight, I utilize the 105 supplemental tower 8. This tower is adapted to support the cable or cables between the fixed towers 2 and 3. The supplemental

tower is formed of side members, comprising legs 16, connected together by a cross member 18, at the top. The side members are separated so that the rails 9 can be laid between them. They are also separated for the purpose of allowing the cars and locomotive to pass through the supplemental tower so that they can pass to the suspended bridge structure.

10 The supplemental tower is supported upon side stringers 10. These side stringers rest upon the embankment 4. The base of the supplemental tower is composed of a base beam 11, on each side, above and parallel with the side stringers 10. This base beam is of sufficient length to afford an adequate supporting foundation for the tower, and so that it will not turn over endwise. The bottoms of the base beams 11 are preferably provided with metal shoes 12, to resist wear and injury to the wood. Rollers 13, engage with the shoes and support the supplemental tower. These rollers are carried upon the side stringers 10. By means 25 of these rollers, the supplemental tower can be moved. When the tower is in position after being adjusted, it is preferably raised by means of jacks, and blocks 14 are inserted between the side stringers and base beam (see Fig. 6). In this position the weight is taken off the rollers and the supplemental tower is immovably held in position. The cables (two being shown in the embodiment chosen for illustration) pass 30 over the supplemental tower and rest upon the saddles 17.

As the work progresses, the suspended bridge structure is moved forward in order to allow the cars to be dumped further into 40 the cut. In order to keep the cable at proper elevation, it is necessary to move the supplemental tower further toward the direction in which the suspended bridge structure is being moved. This movement of 45 the supplemental tower is accomplished by jacking it up enough to allow the blocks 14 to be removed and to allow the tower to rest upon the rollers 13. The tower may then be moved along the stringers 10. The 50 cables resting upon the saddles 17 will be supported at the same time. Any tendency of the supplemental tower to tilt over endwise or sidewise will be resisted by the weight of the cable and the weight of the 55 suspended bridge structure upon it.

Cross beams 15 are inserted at intervals so that they will be under the legs 16 when the tower is in position. They prevent the settling of the tower in the embankment. 60 They also support the tower in the event of the sides of the embankment being washed away. The cross beams 15 are laid upon the top of the embankment at the proper places, the size and number of these beams depending upon the width of the cut, and also

upon the character of the material forming the embankment. Enough of these beams are employed so that an adequate and firm foundation is produced for the supplemental tower.

In Fig. 5, the outline of one side of the embankment as it should be, is illustrated by dotted lines. The solid lines represent the shape that the embankment sometimes assumes owing to the action of rain, frost, or other causes. In this situation, although one side of the embankment may be washed away almost completely, one side of the supplemental tower will be supported by means of the cross beams 15. Owing to the pressure of the cables upon the top of the supplemental tower, the latter will have no tendency to turn over sidewise.

In practice, owing to the very great weights which must be handled, it is necessary to have devices which can be actuated by simple and strong mechanism. As an example of a structure with 1,000 feet span, the towers 2 and 3 may be 70 feet high. Assuming that the cables are of $2\frac{1}{4}$ inches plow 90 steel wire, and that the suspended bridge structure will support about eight cars, then the weight of the cables and structure, without the cars, will be approximately 20 tons. Of this amount, as much as 10 tons will be 95 supported upon the supplemental tower. The weight of the supplemental tower, however, and its height, will be considerably less than that of the fixed towers. In use 100 with a 1,000 foot span and fixed towers of 70 feet in height, the supplemental tower need not be more than 30 feet in height. It may also be made of wood. It is, therefore, very much easier to move than either of the end towers will be. Furthermore, the latter will retain the cables in position while the supplemental tower is being moved. The fact that the supplemental tower has a broad base, not only prevents it from 105 tilting over endwise, but furnishes shoes for 110 action of the rollers. The tower may, therefore, be more expeditiously moved when its position is being shifted. I regard it as very important to have the supplemental tower of such form that it will always remain vertical and in contact with the wire 115 cables. This tower, therefore, does not have to be lowered, when it is moved, and then raised. If such were the case, it could not be raised without the use of a crane, derrick, or some other device which would be difficult of application upon the embankment, and which would entail delay and expense in its use.

In accordance with the provisions of the 125 patent statutes, I have described the principle of my invention, together with the apparatus which I now consider to represent the best embodiment thereof; but I desire to have it understood that the appa- 130

ratus shown is merely illustrative and that the invention can be carried out in other ways.

Having now described my invention, what I claim as new and desire to secure by Letters Patent, is:—

1. A means for extending fillings, having a fixed tower on opposite sides of the cut to be filled; a cable connecting the towers; a bridge structure suspended from the cable, between the towers, and capable of adjustment along the cable as the work progresses; a supplemental tower of less height than the fixed towers, located between one of the fixed towers and the bridge structure, said supplemental tower engaging with the cable and supporting the same, said supplemental tower having an extended base in the direction parallel to the cable; side stringers below the base of said supplemental tower, and parallel therewith; and rollers between said stringers and said base.
2. A means for extending fillings, having a fixed tower on opposite sides of the cut to be filled; a cable connecting the towers; a bridge structure suspended from the cable, between the towers, and capable of adjustment along the cable as the work progresses; a supplemental tower of less height than the fixed towers located between one of the fixed towers and the bridge structure, said supplemental tower engaging with the cable and supporting the same, said supplemental tower having an extended base, in the direction parallel to the cable; means for moving said supplemental tower in the direction toward the other fixed tower as the work progresses, said means permitting the movement of the said supplemental tower while in engagement with and supporting the cable.
3. A means for extending fillings, having a fixed tower on opposite sides of the cut to be filled; a cable connecting the towers; a bridge structure suspended from the cable, between the towers, and capable of adjustment along the cable as the work progresses; a supplemental tower of less height than the fixed towers located between one of the fixed towers and the bridge structure, said supplemental tower engaging with the cable and supporting the same, said supplemental tower having an extended base, in the direction parallel to the cable; and means for moving the said supplemental tower in the direction toward the other fixed tower, as the work progresses, said means permitting the movement of the supplemental tower while in engagement with and supporting the cable.

3. A means for extending fillings, having a fixed tower on opposite sides of the cut to be filled; a cable connecting the towers; a bridge structure suspended from the cable, between the towers, and capable of adjustment along the cable as the work progresses; a supplemental tower of less height than the fixed towers located between one of the fixed towers and the bridge structure, said supplemental tower engaging with the cable and supporting the same, said supplemental tower having an extended base, in the direction parallel to the cable; and means for moving the said supplemental tower in the direction toward the other fixed tower, as the work progresses, said means permitting the movement of the supplemental tower while in engagement with and supporting the cable.

to be filled; a cable connecting the towers; a bridge structure suspended from the cable, between the towers, and capable of adjustment along the cable as the work progresses; a supplemental tower of less height than the fixed towers located between one of the fixed towers and the bridge structure, said supplemental tower engaging with the cable and supporting the same, said supplemental tower having an extended base in the direction parallel to the cable; side stringers below the base of said supplemental tower, and parallel therewith; and rollers between said stringers and said base.

4. A means for extending fillings, having a fixed tower on opposite sides of the cut to be filled; a cable connecting the towers; a bridge structure suspended from the cable, between the towers, and capable of adjustment along the cable as the work progresses; a supplemental tower of less height than the fixed towers, located between one of the fixed towers and the bridge structure, said supplemental tower engaging with the cable and supporting the same, said supplemental tower having an extended base, in the direction parallel to the cable; means for moving said supplemental tower in the direction toward the other fixed tower as the work progresses, said means permitting the movement of the supplemental tower while in engagement with and supporting the cable; side stringers below the base of said supplemental tower, and parallel therewith; and cross beams extending through the embankment and engaging with and supporting the side stringers.

This specification signed and witnessed this 30th day of April, 1912.

JOHN M. BURKE.
